UNITED STATES PATENT OFFICE.

SIGMUND JOSEPH PENTLER AND OTTO R. SHORT, OF WAUSAU, WISCONSIN.

STITCHED-DOWN SHOE.

1,320,797.

Specification of Letters Patent.

Patented Nov. 4, 1919.

Application filed March 10, 1919. Serial No. 281,682.

To all whom it may concern:

Be it known that we, SIGMUND JOSEPH PENTLER and OTTO R. SHORT, both citizens of the United States, and residents of 5 Wausau, in the county of Marathon and State of Wisconsin, have invented certain new and useful Improvements in Stitched-Down Shoes; and we do hereby declare that the following is a full, clear, and exact description thereof.

Our invention relates to new and useful improvements in the manufacture of that type of shoes known to the trade as stitched-down shoes where the edge portion of the 15 upper is turned outwardly to form the securing means of the outer sole. It is in general the object of our invention to improve the manufacture of shoes of this character with respect to the provision of an exceedingly comfortable and durable shoe at a 20 minimum cost.

More particularly, it is an important object of our invention to eliminate the necessity of providing a middle sole, technically 25 known as a doubler, between the inner and outer soles, at the same time providing a structure which may be readily repaired without the necessity of destroying the connection between the inner sole and the 30 upper.

A further important object resides in the provision of an arrangement of structure and operative steps wherein a flat insole is afforded in the finished shoe. A more specific object in this connection resides in the 35 provision of means avoiding the necessity for channeling the insole in the usual manner, thus conducing to the desired smoothness and flatness thereof, and permitting 40 the use of a lighter and cheaper insole than would otherwise be necessary.

A still further object resides in the provision of a shoe of this character which is very pliable and which will at the same time 45 retain its shape for a maximum length of time under conditions of use.

With the above and other objects in view, which will be apparent as the description proceeds, our invention resides in the novel 50 features of construction, combination and arrangement of parts as hereinafter described and defined by the appended claims, it being understood that changes in the precise embodiment might be made by those

skilled in the art, without departing from 55 the spirit of the invention.

Figure 1 is a bottom view of the shoe embodying our invention, portions thereof being broken away and portions being turned back to more clearly show the invention. 60

Fig. 2 is a transverse sectional view through the shoe on the plane indicated by the line 2--2 in Fig. 1.

Fig. 3 is a fragmentary view on a plane similar to Fig. 2 and showing the first step 65 in my improved method.

Fig. 4 is a view similar to Fig. 3 but showing a slightly modified structure.

Referring now more particularly to the accompanying drawings, in carrying out our 70 invention we first tack an inner sole 5 to the usual last A, and this inner sole, by reason of the advantages procured by our improved construction, may be of relatively light and cheap material. We then pull the 75 upper leather 6 and the lining 7 over the last and fasten them temporarily with tacks t. It is noted that the outer edge portion of the inner sole may be beveled as at 8, although this need not necessarily be the case. 80

We then sew the upper leather and lining to the edge portion of the inner sole by stitching 9 which extends through the upper leather and lining and through the edge portions of the inner sole longitudinally between its top and bottom faces, said stitches being arcuate in their extent through the inner sole and emerging from the same at its beveled or other edge portion and at its under face inwardly of its edge portion. The 90 stitching 9 is thus not exposed at the upper surface of the inner sole, said upper surface being thus entirely flat for engagement with the foot of the wearer, whereby to eliminate the necessity of providing the usual sock 95 lining.

The next step is to dispose of the surplus edge portion of the lining 7, either by trimming said edge portion, or as shown in the drawings by cementing the lining edge portion to the bottom of the inner sole it being particularly noted that at any event the lining is positively and permanently secured in place by the stitching 9. The final step is to turn out the edge of the upper leather at 105 the line of engagement of the stitching 9 therewith and to lay the outer sole 10 and apply the usual stitching 11, securing said

outer sole to the edge portion of the upper leather in the usual manner of stitched-down shoes, the usual welting strip 12 being simultaneously fed to the top of the upper leather and secured by the stitching 11.

It is thus noted that the welting strip is entirely free from the upper and that the outer sole is connected with the inner sole only through the medium of the single line 10 of stitching 9 passed through the upper. Striking advantages of flexibility and of wear are procured by this particular arrangement, a machine made shoe constructed by this process being fully as flexible as 15 a hand-turned shoe, since there is no binding action in connection with a plurality of lines of stitches, as in a Goodyear shoe. In our improved shoe the welting strip is thus only utilized for the sake of appearance, 20 and to form a proper binding for the stitching 11, and the welting may be eliminated in so far as the essential connections of our shoe parts is concerned. By leaving the welt free from direct connection with the inner 25 sole, we eliminate a considerable degree of wear and stress on the inner sole, which is a decided advantage since for purposes of economy it is desirable to make the inner sole of relatively weak and cheaper material, and in many types of shoes the inner sole 30 is the first point of failure upon wear.

A slightly modified structure is shown in Fig. 4 wherein an exceedingly cheap form of an insole is provided comprising a leather section 5^a having a facing of canvas 5^b cemented to its under surface, the stitching 9 being applied in the usual manner and passing through the inner sole structure at approximately the juncture of its sections. 40 We thus provide, in a most economical manner, an exceedingly flexible and durable shoe which affords a maximum degree of comfort to the wearer and which may be readily repaired, inasmuch as in repair it is merely necessary to remove the stitching 11 thus 45 releasing the outer sole and welting for substitution by a new outer sole and welting, the securing of the upper leather and lining to the inner sole being in no wise affected, 50 thus retaining the original shape of the shoe.

It is further particularly noted that we entirely avoid the usual channeling operation on the inner sole, thus conducing to a

desired flatness and smoothness of the inner sole, permitting a maximum cheapness of material to be used in the inner sole, and avoid the creation of a hollow space under the inner sole, and the consequent necessity of a filler for such space.

While we have shown and described a preferred embodiment of our invention, it will be appreciated that various changes and modifications of structure and of operative steps may be resorted to to meet differing requirements in the finished shoe and different conditions of the material worked upon, without departing in any manner from the spirit of our invention as interpreted by the appended claims, and which resides essentially in the idea of sewing the upper directly to the inner sole.

What is claimed is:

1. A stitched-down shoe comprising an inner sole, an upper stitched directly to the inner sole and having its edge portion outward from the inner sole, and an outer sole having its edge portion engaged directly with said out-turned edge portion of the upper, a welting strip disposed on said out-turned edge portion of the upper, the inner edge of said welting strip engaging the side of the upper and serving to hold the turned edge portion of the upper against the outer sole, stitching passed through said welting strip, outer sole and the out-turned edge portion of the upper, said welting strip being free from direct connection with the inner sole.

2. A stitched-down shoe comprising an inner sole, an upper and lining stitched directly to the inner sole, the edge portion of the lining being turned inwardly against the inner sole, the edge portion of the upper being turned outwardly from the inner sole, and an outer sole having its edge portion engaged directly with and secured to said out-turned edge portion of the upper, said outer sole being otherwise wholly free from connection with the inner sole, forward of the breast line of the heel.

In testimony that we claim the foregoing we have hereunto set our hands at Wausau, in the county of Marathon and State of Wisconsin.

SIGMUND JOSEPH PENTLER.
OTTO R. SHORT.
